UNITED STATES PATENT OFFICE.

JAMES FAWCETT, OF ROCHESTER, PENNSYLVANIA.

TROLLEY.

1,062,959.

Specification of Letters Patent.

Patented May 27, 1913.

Application filed January 25, 1913. Serial No. 744,122.

To all whom it may concern:

Be it known that I, JAMES FAWCETT, a citizen of the United States of America, residing at Rochester, in the county of Beaver and State of Pennsylvania, have invented 5 certain new and useful Improvements in Trolleys, of which the following is a specification, reference being had therein to the accompanying drawing.

10 This invention relates to trolleys, and the primary object of my invention is to furnish a trolley pole with a shiftable pivoted trolley harp that permits of the wheel of the trolley readily traveling upon a curved section of wire.

Another object of this invention is to provide a trolley that practically eliminates accidental displacement of a trolley due to curved and irregular sections of trolley wire, 20 high speed and such other causes that are a considerable annoyance to the operators of an electric car.

A further object of this invention is to provide a simple, durable and inexpensive 25 trolley that will not interfere with frogs, guard rails, hangers and other overhead construction.

With the above and other objects in view the invention resides in the novel construction, combination and arrangement of parts 30 to be hereinafter specifically described and then claimed.

Reference will now be had to the drawing, wherein:—

35 Figure 1 is a side elevation of the trolley partly broken away and partly in section, and Fig. 2 is a plan of the same.

Further describing my invention in detail with reference to the accompanying 40 drawing, wherein like numerals denote corresponding parts throughout: 1 denotes a portion of a pole having the upper end thereof provided with a flat semi-circular head 2 and said head has a segment-shaped head 2 and said head has a segment-shaped 45 or semi-circular slot 3.

Pivotedly connected to the head 2 by a pin 4 or other fastening means is the bifurcated end 5 of a harp 6. The bifurcated end 5 of the harp provides clearance for the 50 head 2 and revolvably mounted in the bifur-

cation of said harp by a pin 7 or other means is a roller 8 adapted to travel in the slot 3 of the head 2.

Revolvably mounted in the outer end of the harp 6 is a conventional form of trolley 55 wheel 9 adapted to travel against a trolley wire 10 or other electric conductor.

In practice, the harp is preferably made of two pieces, a center web 11 having integral side arms, and it is to this web that 60 the inner bifurcated end of the harp is secured by rivets 12 or other fastening means.

As illustrated by dotted lines in Fig. 2 the harp can swing from one end of the slot 3 to the opposite end, consequently the wheel 65 9 can readily adjust itself to the wire or conductor 10.

The harp in its entirety is made of light and durable metal and is highly efficient in connection with high speed suburban lines. 70

One embodiment of my invention has been illustrated, but it is to be understood that the structural elements are susceptible to such variations and modifications as fall within the scope of the appended claim. 75

What I claim is:—

In a support for trolley wheels, a pole, a flat semi-circular head carried by the upper end thereof and provided near its upper edge with a wide segment-shaped slot, 80 a harp having a bifurcated lower portion mounted upon said head, means for pivotally connecting the lower end of said harp and the lower portion of said plate centrally thereof, a roller revolvably mounted in the 85 furcation of said harp and traveling against the curved edges of said slot, said harp having its upper end bifurcated, the furcation at the upper end of a harp extending in a plane at right angles to the furcation in the 90 lower portion of the harp, said furcation in the upper end of the harp providing means for the mounting of a trolley wheel therein.

In testimony whereof I affix my signature in the presence of two witnesses.

JAMES FAWCETT.
